TOOL COMPANY, OF HOUSTON, TEXAS, A CORPORATION OF TEXAS

ANGLE TOOTH CUTTER

Application filed March 3, 1930. Serial No. 432,588.

This invention relates to cutters for use on roller earth boring drills, particularly cone shaped cutters such as are employed on the Hughes bit shown in Patent 930,759 granted 5 August 10, 1909, although as will be obvious the idea may be adapted to other types of drills.

Such drills have a head, on the forward end of which are supported a plurality of cutters—usually two—of approximately conical shape, mounted and formed to roll with an approximately true rolling motion upon the bottom of the well hole. These cutters when thus positioned, present the base, or largest 10 circumference, of the cutter adjacent the outer wall of the hole. The most difficult portion of the hole to cut lies immediately adjacent the side wall upon the bottom. The cutting teeth upon the cutters penetrate the 15 formation with a sort of chisel stroke, and the material displaced by the cutting teeth must be moved upwardly and laterally by the penetration of the formation by the teeth. Where there is room for the displaced material to 20 do so, this material will be moved into the spaces between the cutter teeth and will be caught by the stream of flushing fluid and carried away to the surface. But where the outer teeth adjacent the side wall of the hole 25 penetrate the formation the material cannot be displaced outwardly because of the wall of the hole, but can only be moved inwardly. As a result the material is not removed and carried away so effectively around the outer 30 margin of the well bottom, and a layer of partially loosened detritus accumulates at this portion of the hole and retards progress. Although the teeth on the cutter are larger along the outer rims of the cutters, the teeth travel 35 in a larger circle and hence cover more area, and the cutting is more difficult because the material displaced by the teeth at that point is not all moved inwardly and brought into the influence of the flushing fluid.

It is an object of the invention to provide a cutter with teeth formed thereon so as to remove the cuttings effectively from the outer portion of the well bottom.

It is desired to cut all portions of the well 50 bottom uniformly, so that the most effective

cutting action of the cutters may be obtained.

It is an object to so form and incline the teeth adjacent the outer portion of the drill that the cuttings will be forced away from the wall of the hole and into a position where 55 they may be reached and carried away by the flushing fluid.

In the drawing Fig. 1 is a side elevation of the lower end of a drill bit equipped with cutters formed to illustrate the invention. 60

Fig. 2 is a plan view of the bottom of a hole and illustrating the tracks of the cutter teeth thereon.

Fig. 3 is a broken elevation of the base of one of the conical cutters. 65

The type of drill here illustrated is in common use. The head 1 of the drill has a V-shaped slot 2 at the lower end on the walls of which are mounted two opposite conical shaped cutters 3.

Positioning the conical cutters in this way brings the sides of the cones on the lower side parallel with the bottom of the hole so as to cut an approximately flat bottomed hole.

The invention resides in the shape and position of the cutting teeth upon the cutters. Heretofore the teeth have been formed in rows longitudinally of the elements of the cones and with the crests presented radially along the cone in lines running from base to apex thereof. The teeth are also in rows circumferentially of the cutting area. 75

In the present cutters the teeth 4 on the inner rows are still formed with the crests running longitudinally of the cutter. In the two outer rows 5 and 6 the teeth are cut on the cone with the crests set at an angle inclined inwardly and rearwardly from the outer circumference of the hole. This will be best understood by reference to the cutter tracks in Fig. 2. The imprints of the teeth are shown at 4', 5' and 6' respectively. The drill head is rotated in a clockwise direction, and it will be seen that the teeth are formed to engage the formation around the outer portion of the hole and move the formation inwardly toward the center with a plow like action. The outer teeth 6 penetrate the formation at such an angle that the material displaced is crowded away from the wall of 100

the hole and into the groove 7 where the flushing fluid will catch it and carry it away. The action of the next inner row 5 will also tend to move the material inwardly, and as a result of the action of the teeth 5 and 6, the penetrating action of the outer teeth is greatly improved, and the progress of the bit is not held up by accumulations around the outer margin adjacent the wall.

- 10 It will be noted that the two cutters are mates. The rows of teeth of one cone are opposed to the grooves between the rows of teeth upon the mating cone. Thus each cutter cuts its own track upon the bottom of 15 the hole. The view of the bottom shown in Fig. 2, therefore, shows the track of but one cutter. The track of the other cutter would be similar, but would lie in the uncut portions 8 between the tracks of the first cutter.
- 20 It is also important that all the cutters have the teeth thereon similarly inclined to push the material inwardly.

The advantages of this type of cutter have already been noted. The cutters will cut 25 faster and wear better, because the drill is not held up by the material adjacent the well wall. This portion of the hole will be cut effectively, and the material will be moved inwardly where it can be carried away by the flushing 30 fluid.

What is claimed as new is:

1. A cutter for well drills, said cutter being of approximately conical shape, teeth formed in endless circumferential rows on 35 said cutter, the rows adjacent the apex thereof being extended radially away from said apex, the teeth adjacent the base thereof being inclined relative to the radius of each cutter to move the material toward the said 40 apex as said drill is rotated.

2. A cutter for well drills, said cutter being of approximately conical shape, teeth formed in endless circumferential rows on said cutter, the rows adjacent the apex thereof being extended radially away from said apex, the crests of said teeth adjacent the base thereof being inclined inwardly and rearwardly from the forward advancing ends 45 of said teeth, so as to move the material cut thereby inwardly.

3. In a well drill, a head, two opposed conical shaped cutters mounted on the forward end thereof, and separate rows of teeth on both said cutters, each tooth on the outer 55 row having a cutting edge inclined inwardly and rearwardly from the direction of rotation to move the material on the well bottom away from the wall of the hole.

In testimony whereof, we hereunto affix 60 our signatures, this 28th day of February, A. D., 1930.

SETH EVANS.
JOHN A. HERRINGTON.
